3 SHEETS—SHEET 3.

UNITED STATES PATENT OFFICE.

ARTHUR SAMUEL FRANCIS ROBINSON, OF BARSHAM, BECCLES, ENGLAND.

GRIPPING-TOOL.

979,563.

Specification of Letters Patent. Patented Dec. 27, 1910.

Application filed April 2, 1909. Serial No. 487,425.

To all whom it may concern:

Be it known that I, ARTHUR SAMUEL FRANCIS ROBINSON, a subject of the King of Great Britain and Ireland, residing at 5 Barsham, Beccles, in the county of Suffolk, England, have invented Improvements in Gripping-Tools, of which the following is a specification.

This invention relates to smiths' tongs, 10 pliers, and other similar gripping tools, which, as ordinarily constructed cannot have their jaws opening parallel or approximately parallel owing to the jaw levers being crossed at the fulcrum (as in scissors), 15 and where, as in specially constructed power pliers, a parallel motion is obtained, the jaw opening is very limited, involving for varied sizes of work to be gripped the use of a number of different sizes of tools.

20 To make one pair of smiths' tongs or one pair of pliers take the place of many or render them suitable for a large range of the ordinary work for which tongs and pliers are required, including gas pipe and 25 ordinary spanner work, tongs, pliers and similar tools are according to this invention provided with two jaws one of which is extended to form a hand grip and has fulcrumed to it a lever that is formed with 30 a corresponding hand grip and is connected at the side of the fulcrum remote from the grip by a link to the other jaw which is formed with a lateral extension pivoted to its fellow at a point between the lever ful- 35 crum and the hand grip, the pivotal connec- tions or certain of them being capable of adjustment whereby the range of opening and power to grip may be made suitable for a large variety of work. In some construc- 40 tions a device can be provided adapted to secure the two hand grips against relative movement and thereby lock the jaws in a work gripping position. In such cases the hand grip extension of the one jaw can be 45 adapted to be readily secured to a bench or other suitable support for the purpose of acting as a vise.

50 Figures 1 and 2 of the accompanying illustrative drawings show in elevations at right angles to each other a pair of pliers constructed according to this invention. Fig. 5 is a detail view of a part thereof. Figs. 4 and 5 are similar views to Figs. 1 and 2 showing a pair of smiths' tongs according to this invention. Figs. 6 and 7 are also

similar views to Figs. 1 and 2 showing a modified construction of smiths' tongs. Fig. 8 is a detail view of parts thereof. Fig. 9 shows in elevation gas pipe gripping dies adapted to be secured to the jaws of 60 the improved gripping tools. Fig. 10 is a plan of the dies shown in Fig. 9. Fig. 11 shows in elevation and Fig. 12 in plan a device for locking the jaws in work gripping 65 positions, applied to the hand grip portions of the appliance, Fig. 11 also illustrating means for securing the appliance to a support.

In the several constructions illustrated the link *a* is in the form of a bridle wherein 70 the gripping jaws *b*, *b*¹ are a sliding fit and is adjustably pivoted at *c* to one jaw *b* that has an L shaped extension *d* the foot of which is adjustably pivoted at *e* about mid-way down the lever arm *f* of its opposing 75 jaw *b*¹ (hereinafter referred to as the opposing jaw); the power closing and opening lever *g* is pivoted at one end to the bridle link *a* at *h* and is fulcrumed adjustably at *k* in a recessed extension *m* at the back of 80 and below the gripping portion of the opposing jaw. Gripping the power lever *g* and the arm *f* so as to press them toward each other causes the power lever *g* to draw 85 the jaws *b* and *b*¹ together by means of the bridle link *a*.

The work gripping portions of the jaws *b*, *b*¹ may be separately made and each riveted between two steel plates forming the remaining portions *d* and *f* of the jaws 90 (Figs. 1, 2, 6 and 7), a portion of the handle *f* passing between the plates of the L shaped jaw extension *d*. The bridle link *a* can be formed of one U shaped bent link riveted at the open end by a shouldered pin *h* to 95 which the end of the power lever *g* is pivoted, as shown in Figs. 1, 2, 3, 4 and 5.

*h*¹ *h*¹, Fig. 3, are washers on the pin *h* between the sides of the link *a* and the lever *g*, so that the link sides can be straight, 100 as shown, instead of being bent inwardly at their outer ends. Instead of a shouldered pin *h*, the link ends may, as shown in Figs. 6 and 8 be clamped by a bolt *h*² to a ferrule *h*³ on which the lever *g* is pivoted. The ferrule *h*³ is of such length as to prevent the lever end being nipped. This construction 105 enables the link *a* to be removed when the bolt *h*² is withdrawn, an arrangement that is desirable when the jaws *b*, *b*¹ are wider 110

than the gap between the link sides. Series of pin holes o are provided in the bridle link a and foot of the extension jaw d so that the jaws b , b^1 may be brought closer together or set farther apart parallel or at any desired angle.

To increase or decrease the range of action of the power lever g , the fulcrum pin h in the recessed extension m formed in the back 10 of the opposing jaw b^1 may be placed in one or other of holes p provided therefor.

By withdrawing its pivot pins c and e the jaw b may be removed and a spare one formed especially for gripping gas pipe can 15 be inserted in its place, or it or the opposing jaw b^1 , or both, may be formed to receive a gas pipe die q , see Figs. 9 and 10, which, for instance, may be recessed at the back to fit the jaw face and be held in position by a pin r passing through it and the jaw. Each 20 adjusting pin c , e and h is threaded at one end which is screwed into the one side of the bridle or jaw so as to secure the pin in place.

25 When the arm f is formed of plates riveted to the jaw b^1 as shown in Figs. 1, 2, 6 and 7, a block or plate of fiber or other suitable material can be riveted between the plates thereof.

30 The foot of the jaw extension d may, as shown in Fig. 4, be extended and formed with holes o^1 adapted to receive a locking pin behind the arm g that prevents the jaws opening.

35 In the pliers shown in Fig. 1, the jaws b , b^1 are formed with serrated recesses suitable for gripping gas pipes and the like.

t , Figs. 6 and 7, is a slotted locking link pivoted at u to the arm g and extending 40 between the plates of the arm f , w being a bolt mounted in the arm f and extending through the slot of the link t and washers x located between the link t and the plates of the arm f .

45 y is a thumb nut on the bolt w whereby the link t can be frictionally gripped, the side plates of the arm f springing sufficiently to admit of such gripping.

The slotted locking link t may, as shown 50 in Figs. 11 and 12 and in dotted lines in Figs. 1 and 2, be in the form of a U shaped bent link that embraces the arm f .

To enable the appliance to be used as a vise the arm f may be formed with holes 55 whereby it can be readily screwed to a suitable support 1, as shown in Fig. 7 or be bolted between angle plates 2 screwed to such support, as shown in Fig. 11 and in dotted lines in Figs. 1 and 2.

60 What I claim is:—

1. In a gripping tool, a gripping jaw formed with a pivot hole and provided beyond said pivot hole with an L-shaped extension formed with a number of pivot holes 65 an opposing jaw provided with a hand grip

extension and formed with a pivot hole between the jaw part and hand grip, a pivot pin adapted to engage any one of the holes of the L-shaped extension of said gripping jaw and the pivot hole of said opposing jaw, 70 a lever pivoted to said opposing jaw and formed with a corresponding hand grip, a link pivoted to said lever and formed with a number of pivot holes, and a pivot pin adapted to engage any one of the holes of 75 said link and the pivot hole of said gripping jaw.

2. In a gripping tool, a gripping jaw formed with a pivot hole and provided beyond said pivot hole with an L-shaped extension 80 formed with a number of threaded pivot holes, an opposing jaw provided with a hand grip extension and formed with a pivot hole between the jaw part and hand grip, a threaded pivot pin adapted to engage any one of the holes of the L-shaped extension of said gripping jaw and the pivot hole of said opposing jaw, a lever pivoted to said opposing jaw and formed with a corresponding hand grip, a link pivoted to said 85 lever and formed with a number of threaded pivot holes, and a threaded pivot pin adapted to engage any one of the holes of said link and the pivot hole of said gripping jaw.

3. In a gripping tool, a gripping jaw 90 formed with a pivot hole and provided beyond said pivot hole with an L-shaped extension formed with a number of pivot holes, an opposing jaw provided with a hand grip extension and formed with a pivot hole between the jaw part and hand grip, a pivot pin adapted to engage any one of the holes of the L-shaped extension of said gripping jaw and the pivot hole of said opposing jaw, a lever adjustably pivoted to said opposing jaw and formed with a corresponding hand grip, a link pivoted to said lever and formed with a number of pivot holes, and a pivot pin adapted to engage any one of the holes of said link and the pivot hole 95 of said gripping jaw.

4. In a gripping tool, a gripping jaw formed with a pivot hole and provided beyond said pivot hole with an L-shaped extension 100 formed with a number of pivot holes, an opposing jaw provided with a hand grip extension and formed with a main pivot hole between the jaw part and hand grip and with a number of lever pivot holes between the jaw part and the main pivot hole, a pivot pin adapted to engage any one of the holes of the L-shaped extension of said gripping jaw and the main pivot hole of said opposing jaw, a lever formed with a number of pivot holes and formed with a hand grip, 105 a pivot pin adapted to simultaneously engage any one of the pivot holes of said lever and any one of the lever pivot holes of said opposing jaw, a link pivoted to said lever and formed with a number of pivot holes, 110

115

120

125

130

and a pivot pin adapted to engage any one of the holes of said link and the pivot hole of said gripping jaw.

5. In a gripping tool, a gripping jaw formed with a pivot hole and provided beyond said pivot hole with an L-shaped extension formed with a number of pivot holes, an opposing jaw provided with a hand grip extension and formed with a main pivot hole 10 between the jaw part and hand grip and with a number of lever pivot holes between the jaw part and the main pivot hole, a pivot pin adapted to engage any one of the holes of the L-shaped extension of said gripping jaw and the main pivot hole of said opposing jaw, a lever formed with a pivot hole and with a hand grip, a pivot pin adapted to engage the pivot hole of said lever and any one of the lever pivot holes of 15 said opposing jaw, a link pivoted to said lever and formed with a number of pivot holes, and a pivot pin adapted to engage any one of the holes of said link and the pivot hole of said gripping jaw.
- 20 6. In a gripping tool, a gripping jaw formed with a pivot hole and provided beyond said pivot hole with an L-shaped ex-

25 tension formed with a number of threaded pivot holes, an opposing jaw provided with a hand grip extension and formed with a main pivot hole between the jaw part and hand grip and with a number of lever pivot holes between the jaw part and the main pivot hole, a threaded pivot pin adapted to engage any one of the holes of the L-shaped extension of said gripping jaw and the main pivot hole of said opposing jaw, a lever formed with a number of pivot holes and formed with a hand grip, a threaded pivot pin adapted to simultaneously engage any one of the pivot holes of said lever and any one of the lever pivot holes of said opposing jaw, a link pivoted to said lever and formed with a number of threaded pivot holes, and a threaded pivot pin adapted to engage any one of the holes of said link and the pivot hole of said gripping jaw.

Signed at London England this 24 day of March 1909.

ARTHUR SAMUEL FRANCIS ROBINSON.
